(57) **CLAIM**

The ornamental design for a plank tool, as shown and described.

DESCRIPTION

FIG. 1 is a front perspective view of a plank tool.
FIG. 2 is another front perspective view of the plank tool of FIG. 1 in a use state.

FIG. 3 is a left side view of the plank tool of FIG. 2.

FIG. 4 is a right side view of the plank tool of FIG. 2.

FIG. 5 is a front view of the plank tool of FIG. 2.

FIG. 6 is a rear view of the plank tool of FIG. 2.

FIG. 7 is a bottom view of the plank tool of FIG. 2; and,

FIG. 8 is a top view of the plank tool of FIG. 2.

The dash-dot broken lines immediately adjacent to shaded areas in the drawings define the bounds of the claimed design and form no part thereof.

The remainder of the broken lines in the drawings depict portion of the plank tool that form no part of the claimed design.

1 Claim, 8 Drawing Sheets
